CLAIM

The ornamental design for a vehicle side panel as shown and described.

DESCRIPTION

FIG. 1 depicts a front, left, upper perspective view of a vehicle side panel showing our new design.

FIG. 2 depicts a front, right, lower perspective view thereof;

FIG. 3 depicts a front view thereof;

FIG. 4 depicts a back view thereof;

FIG. 5 depicts a right side view thereof;

FIG. 6 depicts a left side view thereof;

FIG. 7 depicts a top view thereof; and,

FIG. 8 depicts a bottom view thereof.

The dash-dot-dash line illustrates a boundary line that surrounds the claimed design. The broken lines shown in the figures are included for the purpose of illustrating portions of the vehicle side panel and form no part of the claimed design.

1 Claim, 8 Drawing Sheets
